GUNFIRE CONTROL TRAINING APPARATUS

Gunnar Ekström, Stockholm, and Paul Wilhelm Dietmann, Jonkoping, Sweden, assignors to Areco Aktiebolag, Stockholm, Sweden, a Swedish joint-stock company

Application November 27, 1944, Serial No. 565,296
In Sweden September 7, 1942

15 Claims. (Cl. 35—25)

1

This invention relates to apparatus for the training of operators of gun-fire control instruments including range finders and cannon laying apparatus, and it has for its object to provide means whereby an effective training and testing under realistic conditions is made possible.

The invention consists in the construction and novel combination and arrangement of parts hereinafter described, illustrated in the accompanying drawings and pointed out in the claims hereunto appended.

Various embodiments of the invention are shown diagrammatically in the accompanying drawings:

Fig. 1 is a perspective view showing a practice apparatus for following a target,

Figs. 2 and 3 are separate views of a registering and a target image device adapted to be used in the apparatus.

Fig. 4 is a perspective view of a cannon laying exercise apparatus.

The apparatus shown in Fig. 1 has for its object to permit practice in following movable aerial targets in such manner as takes place in certain central station instruments for calculating firing data. The various parts of the apparatus are carried by a framework not shown as an entirety, on the upper part 1 of which is rotatably carried a table 2 which corresponds to the movable base of the central instrument. A pedestal 3 on the table carries a T-shaped part 4, 5 provided with two eye pieces 18 and also with an objective of a telescope. The other, L-shaped part 6, 7 of the telescope, is suitably carried rotatably on the table in a bearing 8 with its limb 6 forming an extension of the central part 5 of the T-shaped part. The table can be rotated by means of a handwheel carried thereon or a crank 9, for example by the handwheel being connected through a suitable transmission gear with a spur-wheel 10 which engages with a toothed rim 11 on the frame 1. Two other handwheels 12, 13 carried on the table are connected through suitable spur-wheel gearing with a horizontal spindle 14 carried on the table and which is connected by a spur-wheel 15 with a toothed rack 16 carried on the table and movable vertically. The rack 16 engages with a spur-wheel 17 connected with the limb 6. By means of the handwheel 9 and/or one of the handwheels 12 and 13, the telescope 7 can be traversed and/or elevated on to an object which, by prisms or the like suitably arranged in the telescope, can be observed by the eye pieces 18. These

2

and the handwheels have preferably the same mutual arrangement as the corresponding parts on a central instrument.

An arm 19 mounted on the apparatus carries in front of the objective aperture 1a of the telescope a holder 20 for a reticule or cross-wires, the image of an aircraft or other target image, which by means of a suitable illuminating device fitted on the holder, can be illuminated. The arm 19 is oscillatable about the same horizontal and vertical axes as the part 7 of the telescope, for example by being carried by means of pivot 21 coaxial with the limb 6 on an arm 22 which is fitted on a hollow spindle 23 carried rotatably with respect to the table 2 and coaxially with the axis of rotation thereof. For the shifting of the target image in a predetermined path, the arm 19 is, in the embodiment shown, mechanically connected with a driving arrangement mounted in the framing under the table 2. This driving device comprises two cam discs 24, 25 which may be fitted so as to be easily interchangeable on spindles 26, 27 which by means of suitable transmission gearing are connected with an electric motor 28, suitably common for both, the transmission being preferably such that the cam discs make one revolution in a minute or some other period of time for a presumed aerial attack. The cam disc 24 imparts a predetermined movement of rotation to the spindle 23, by means of a toothed rack 30 which is movable horizontally at right angles to the spindle 26 and engages a toothed wheel 29 secured to the spindle 23, the rack 30 bearing by means of a roller 31 and, if desired, under spring pressure against the edge of the cam disc 24. The cam disc 25 has to impart to the arm 19 a predetermined oscillating movement about the pivot 21, for which purpose the cam disc 25 controls a vertically movable rack 35 which is connected to the lower end of a rod 34 which is axially displaceable in the spindle 23 but is rotatable therewith. The upper end of the rod 34 is firmly connected to a vertical rack 33 which engages with a toothed sector 32 on the arm 19.

On the rotation of the cam discs 24, 25, the target image is shifted in a path predetermined by the form of the cam discs, and the practice party has to follow the target image as exactly as possible by the telescope, preferably provided with cross wires or the like, by means of the adjusting or setting device consisting of the handwheels and the associated members. A continuous recording of the adjustment of the telescope during this operation is valuable. The

divergencies of the telescope in the direction of the target image either in traversing or elevating can be recorded by two separate recording means, each of which is operatively connected through a differential gear with the corresponding parts of the driving device and the adjusting device. In the embodiment shown, one recording medium 36 is, for the sake of simplicity, fitted on the spindle 37 of a planet wheel 38 which is in engagement with two toothed wheels 39, 40 which are so operatively connected with the toothed wheel 29, and with a toothed wheel 41 rotatable with the table 2, that the recording medium 36 is in a zero position as long as the telescope is correctly directed in the traversing direction on to the target image. The second recording medium 42 can be arranged in a corresponding manner to obtain by a differential gear 43 the difference in movement between a toothed wheel 44 actuated by the rack 35 and a toothed wheel 45 which engages with a member 46 which is axially displaceable on the rod 34 but not rotatable and which is operatively connected in the axial direction with the rod 16. The recording media can be arranged adjacent to each other, each to record on a separate or a common paper strip 47 continuously moved forward by clockwork or the like not shown on the drawing.

The telescope or aiming apparatus can, however, be also connected in such manner with a single recording stylus resting against a stationary support that the movement thereof in two directions perpendicular to each other corresponds to the movements of the instrument in the traversing or elevating directions. For example, with the embodiment shown in Fig. 1, the differential gearing and the members connected thereto would be replaced by a recording device coinciding in principle with that shown in Fig. 2, which comprises two parallel spindles 50, 51, a slide 52 carried thereon, and a holder 53 for a recording stylus displaceable at right angles to said spindles. The holder 53 is in threaded engagement with a screwthreaded spindle 54 which is carried in the slide and is rotated from the spindle 50 by means of a bevel wheel drive 55. The spindle 51 is screwthreaded and is in threaded engagement with the slide 52. When the spindles 50 and 51 are suitably connected with the toothed wheels 41 and 45, respectively, the recording stylus will describe on a support 56, a path 57 corresponding to the arrangement of the telescope, the support consisting preferably of a sheet of paper on which a curve 58 indicating the predetermined path of the target image has been previously marked. Such a recording device is particularly suitable when the target image is not arranged on the apparatus itself.

In order to make the exercise more realistic, the target image on the holder 20 can be replaced by a stepwise movable member such as a disc, a band or the like, showing a number of different images of a target and which is arranged to convey these images one after the other into a position of presentation with respect to the aiming apparatus. According to Fig. 3, the holder 20 is thus provided with a rotatable disc 60 showing a number of different pictures 61 of an aircraft and is provided with a preferably electro-magnetic stepwise feeding device by which the pictures or images appear one after the other in an aperture 62 in the holder. A corresponding change of the picture or image may also be suitable when the target image con-

sists of a photograph produced by a projector and which, like the arm 19, may be adjustable in the traversing and elevating directions.

An apparatus agreeing in principle with Figure 1 can also be used for exercise in following the target with smaller anti-aircraft weapons for direct firing, e. g. those with a reflex sight for altitude aiming and a reflex sight for horizontal aiming. The target arm 19 is here provided with two target images adjacent to each other and the telescope 4-1 is replaced by two reflex sights adjustable with a handwheel for elevation and deflection, respectively, or by simple tubes with cross wires, which are located as close as possible to the target image.

It should be obvious that the invention can also be used with apparatus where the direction of the target is variable only in one plane. The invention can thus be used with advantage in exercises with range finders which are provided with a measurement drum rotated by the service attendants, for example until the two images produced by the objectives of the apparatus, of an incidence line on the target, come opposite to each other. The measuring drum may here be connected through a screw drive with a recording stylus which, for example, bears against a paper strip continuously fed forward in its longitudinal direction. Instead of an actual target, a target image movable in a predetermined path can also be used in this case, a front lens being arranged in front of each objective and a target image or a datum mark being arranged in front of the lens at focal distance. The one target image is here driven laterally for example by means of an easily interchangeable cam disc driven by a motor, so that the sighting lines of the two objectives of the range finder through the corresponding target images intersect each other at a distance which corresponds to the distance of the imagined air target which runs through a definite imagined path. Instead of recording the absolute value of the measured distance, it is possible as with the embodiment according to Figure 1, to record its relative value or its divergence from the distance corresponding to the form of the cam disc.

The invention can also be used with such apparatus where instead of an aiming apparatus some other kind of tracking member is fitted. In this the primary value, e. g. the direction of an assumed target can be given by means of a movable pointer, the setting mechanism being in driving connection with a tracking member in the shape of another corresponding pointer (follower pointer). The two pointers are connected with the recording device. In the cannon laying exercise apparatus shown in Figure 4, one of the firing data, e. g. the timing period or the lateral angle to the impact point, is given by means of a disc 70 provided with an index or pointer, on a rotatably carried spindle 71, and this spindle receives a predetermined rotary movement by means of a driving device which comprises a cam disc 73 driven by a spring motor and regulator, or by a synchronous motor 72 and a rack 74 actuated thereby which engages with a toothed sector 75 on the spindle 71. There is rotatably carried on the spindle a follower pointer in the form of a disc 76 provided with an index and connected with a toothed wheel 77, the latter being in such driving connection, by means of a transmission gear 78, with a handwheel 79, fitted on a spindle 80 of a setting mechanism, that on the rotation of the handwheel the disc 76 is rotated

in the same direction. By means of a second gearing 81, the handwheel can be placed in driving connection with a timing apparatus or a cannon or a casement therefor. The adjustment of the setting mechanism in relation to the variable primary value given by the pointer 76 is suitably recorded on a paper strip 82 by means of a recording medium provided with a recording stylus and which is operatively connected through a differential gear with the driving device and the setting mechanism. In the embodiment shown, the recording medium 83 is, for the sake of simplicity, shown on the pivot of a planet wheel 84, which pivot is oscillatably carried on the spindle or shaft 71, the planet wheel 84 engaging with a toothed wheel 85 secured to the spindle 21 and with a toothed wheel 87 connected with the spindle 80 through a pinion gearing 86. Naturally, the absolute value of the firing data introduced can also be recorded. In the embodiment shown the said firing data is given by means of a pointer. This can naturally be connected through a fine adjustment with a corresponding follower pointer connected to the pointer 76. A number of apparatus according to Figure 4 can be combined for a corresponding number of firing data into a unit and be provided with a common driving device. The driving device can also consist of a step-by-step receiver motor which by means of a cable is connected to a corresponding transmitter in a central instrument, or to a transmitter which is actuated by the corresponding adjusting handwheel 9 or 12 of an exercise apparatus according to Figure 1 said receiver and transmitter forming part of a self-synchronous electric transmission system known per se, such linking of different apparatus serving the purpose of training teamwork. Such systems are disclosed in United States Patent Nos. 1,813,543 and 1,976,727. Each recording device is suitably provided with an electromagnetically actuated recording stylus to mark the point of time, for example, of the firing of an imaginary cannon, this making it possible afterwards to ascertain the degree of accuracy at such instant.

What we claim is:

1. An apparatus of the character described comprising a movable target member, a driving device operatively connected with said target member for imparting a determined movement thereto, a setting mechanism, a tracking member under positive control of said setting mechanism for performing a movement corresponding to that of said target member, and a recording device including a stylus operatively connected with said setting mechanism for continuously and graphically recording the movement of said tracking member.
2. An apparatus of the character described, comprising a movable target member, a driving device operatively connected with said target member for imparting a determined movement thereto, a setting mechanism, a tracking member under positive control of said setting mechanism for performing a movement corresponding to that of said target member, and a recording device including a stylus operatively connected through a differential gear with said driving device and said setting mechanism so as to record the movement of said tracking member relatively to that of said target member.
3. An apparatus of the character described, comprising a direction indicating member mounted to swing about a center, a driving device operatively connected with said indicating

- member for imparting a determined movement thereto, a tracking member swingable about said center and capable of being set in directions indicated by said indicating member, a setting mechanism in driving connection with said tracking member, and a recording device including a stylus operatively connected with said setting mechanism for continuously and graphically recording the direction imparted to said tracking member.
4. An apparatus for training in laying a gun, comprising in combination, a target pointer mounted to swing about an axis, a cam-operated driving device operatively connected with said target pointer for imparting a predetermined movement thereto, a tracking pointer mounted to swing about said axis in the proximity of said target pointer, a setting mechanism in driving connection with said tracking pointer, and recording device including a stylus operatively connected through a differential gear with said driving device and said setting mechanism so as to record the movement of said tracking pointer relatively to that of said target pointer.
  5. An apparatus of the character described, comprising a movable target, a driving device operatively connected with said target for imparting a determined movement thereto, a telescope directable at said target, a setting mechanism in driving connection with said telescope, and a recording device including a stylus operatively connected with said setting mechanism for continuously and graphically recording the direction imparted to said telescope.
  6. An apparatus of the character described, comprising a movable target, an aiming apparatus mounted to swing universally about a center and directable at said target, a driving device operatively connected with said target for imparting a determined movement thereto vertically as well as laterally relatively to said aiming apparatus, and a recording device operatively connected with said aiming apparatus for continuously and graphically recording the direction imparted thereto.
  7. Apparatus according to claim 6, wherein said driving device comprises two interconnected cams adapted to move said target in the vertical and lateral direction respectively.
  8. An apparatus of the character described, comprising a movable target, an aiming apparatus mounted to swing universally about a center and constructed to permit two persons to aim simultaneously at said target, a driving device operatively connected with said target for imparting a determined movement thereto vertically as well as laterally relatively to said aiming apparatus, and a recording device operatively connected with said aiming apparatus for continuously and graphically recording the direction imparted thereto.
  9. An apparatus of the character described, comprising a direction indicating arm mounted to swing universally about a center, a tracking member mounted to swing universally about the said center and capable of being set in directions indicated by said arm, a driving device operatively connected with said arm for imparting a determined movement thereto vertically as well as laterally, a setting mechanism in driving connection with said tracking member, and a recording device including a stylus operatively connected with said setting mechanism for continuously and graphically recording the direction imparted to said tracking member.

10. A practice apparatus for following a target, comprising in combination, an arm mounted to swing about a center, a target image device carried by said arm; an aiming apparatus directable on said target image; and a recording device arranged to record the direction of said aiming apparatus.

11. Apparatus according to claim 8; wherein said aiming apparatus comprises a telescope with two eye-pieces for one and the same objective.

12. Apparatus according to claim 6, wherein said recording apparatus comprises a recording stylus cooperating with a stationary support and operatively connected to said aiming apparatus in such manner that its movement in two directions perpendicular to each other corresponds to the movements of said aiming apparatus in the vertical and lateral direction.

13. A practice apparatus for following a target, comprising in combination, a target direction indicating arm mounted to swing about a center, a driving mechanism for said arm, an aiming apparatus, a manually operated device for adjusting said aiming apparatus to agree in direction with the direction indicated by said arm, and a recording device arranged to record the adjustment of said aiming apparatus, said aiming apparatus together with said adjusting device being mounted to swing about a vertical axis, and said driving mechanism being stationarily mounted and mechanically connected with said arm by means of a member coaxial with the said vertical axis of said aiming apparatus.

14. A practice apparatus for following a target,

comprising a target direction indicating arm, an adjustable aiming apparatus, and a recording device arranged to record the adjustment of said aiming apparatus, said aiming apparatus comprising a part rotatable about a horizontal axis and one vertical axis intersecting this, and said arm being oscillatable about the same two axes.

15. Apparatus according to claim 10, wherein said target image device comprises a stepwise-movable member having a plurality of different images of a target and being arranged to convey said images one after the other into a position of exposure with respect to the said aiming apparatus.
